WIRE REELING MACHINE

Kenneth O. Marion, Detroit, Mich.

Application May 11, 1949, Serial No. 92,545

4 Claims. (Cl. 242—54)

1

This invention relates to improvements in wire reeling machines, and refers particularly to a machine for winding any odd length of wire onto a reel, and also includes means for ready removal of the wire from the machine after it has been wound upon the reel.

There is a large and constant demand for odd lengths of wire short of a full reel, but to take off and coil a length of wire, or to wind an odd length onto another reel, requires so much time and labor that generally wholesalers and distributors will not do this, consequently users are forced to buy a full reel and transport it to the job. Again it may be pointed out that whereas in some cases it is desirable to handle wire of the length desired from a reel onto which it has been wound, in others, particularly if the wire is relatively light and the length is relatively short, it is easier to handle it in a coil after removal from the reel.

This invention aims, among other things, to provide a wire reeling machine including elevating means so that a reel may be quickly and easily mounted thereon for rotation, and as readily removed after the wire has been wound thereon.

Another object of the invention is to provide a wire reeling machine including means for rotating the reel onto which the wire is wound, and automatic means for preventing rotation of the machine when the reel is being raised or lowered.

A further object of the invention is to provide a wire reeling machine including a collapsible reel from which a coil of wire may be easily removed, and wherein means are provided for facilitating the tying of a coil prior to its removal from the reel.

Having thus briefly stated some of the objects and advantages of the invention, I will now describe it in detail with the aid of the accompanying drawings, in which:

Figure 1 is a perspective view of one form of the invention, and

Figure 2 is a longitudinal section thereof.

Figure 3 is a view taken on the line 3—3 of Figure 2 with a portion of the casing broken away.

Figure 4 is a section on the line 4—4 of Figure 2.

Figure 5 is an enlarged section on the line 5—5 of Figure 2.

Figure 6 is a section on the line 6—6 of Figure 2, showing the lower portion of a reel supported on the base.

2

Figure 7 is a perspective view showing part of the machine including a modified form of reel.

Figure 8 is a cross sectional view of the reel shown in Figure 7.

5 Figure 9 is a section on the line 9—9 of Figure 8.

Figure 10 is a side view, partly in section, of the reel shown in Figure 8 with wire coiled thereon, and

10 Figure 11 is an enlarged section on the line 11—11 of Figure 9.

Referring to the drawings, 1 designates a bed having a platform 2 formed at one extremity, and an opening 3 through the said bed intermediate of its length and width to receive a vertically movable base 4 having two spaced upwardly projecting ribs 4a thereon which extend longitudinally. Suitably secured upon the bed 1 adjacent opposite extremities of the openings

15 3 are standards 5 and 5a each of which includes two transversely spaced vertical guides 6. Extending vertically through the base 4 and supported for rotation thereon as by thrust bearings

7 are threaded spindles 8, each of which is positioned between one transversely spaced pair of guides 6 and has its upper extremity rotatably mounted in a bearing 9 secured to the standard

20 5, or 5a. In engagement with each threaded spindle 8 is a nut 10 upon which a supporting arm 11 rests, and each arm is suitably secured to the adjacent extremity of the base 4 centrally of its width. The nuts 10 and arms 11 are held against rotation with the threaded spindles 8 by the spaced guides 6.

25 Mounted on the platform 2 is an electric motor 12 and a gear box 13. Secured on the shaft of the said motor is a pulley 14 having a belt 15 around it which also passes around the pulley

30 16 fixed on a drive shaft projecting from the gear box 13; and secured upon a driven shaft extending from the said gear box is a sprocket 18. Fixed on the lower extremities of the threaded spindles 8 are bevel gears 19, and supported for rotation in bearings 20 dependently mounted on the bed 1 is a shaft 21 having bevel gears 22 fixed thereon each of which meshes with one of the gears 19. Fixed around the shaft 21 is a sprocket 23 which is driven by a chain 24 that also passes around the sprocket 18. Thus when

35 the motor 12 is in operation the threaded spindles 8 are turned in one direction or the other to raise or lower the base 4.

40 Secured between the standard 5 and another standard 26 mounted on the outer extremity of the platform 2 and above the latter is a stand 27

which supports a gear box 28 having stepped pulleys 29 fixed on an outwardly projecting drive shaft. Mounted on the platform 2 substantially beneath the gear box 28 is an electric motor 30 having stepped pulleys 31 secured around its shaft. Extending around one of the pulleys 29 and one of the pulleys 31 is a belt 32, and fixed on a driven shaft extending from the gear box 28 is a sprocket 30. Mounted in suitable bearings 34 on the standards 26 and 5 is a shaft 35 fixed around which is a sprocket 36 driven by a chain 37 which also extends around the sprocket 33. Fixed on one extremity of the shaft 35 which extends over the base 4 is a faceplate 38. Thus when the motor 30 is in operation the shaft 35 and faceplate 38 are rotated.

Formed axially in the outer face of the faceplate 38 is a recess 39, and extending through the said faceplate are a plurality of concentrically located threaded openings 40 in engagement with each of which is a screw 41 having an enlarged head. The faceplate may either be employed for supporting and rotating a conventional reel 42 shown in Figures 1, 2 and 5, or a collapsible reel 43 shown in Figures 7 to 11, inclusive.

Referring to Figures 1, 2 and 5, wherein a conventional reel 42 is shown, 44 designates a driving disc having a radial arm 45 projecting from its periphery, and formed longitudinally through the said arm intermediately of its length and width is a slot 46. Mounted on opposite sides of the arm 45 are two plates 47 and 48 which are secured to one another by screws 49 extending through the slot 46 so that they may be adjusted along the said arm. Projecting from the plate 48 is a drive pin 50 adapted to be inserted in an opening 51 formed in one face of the reel 42. The reason for providing for movement of the plates 47 and 48 along the arm 45 is so that the pin 50 may be positioned to engage openings 51 provided at different distances from the axes of different reels 42. Extending through the disc 44 are a plurality of concentrically arranged arcuate slots 52 each of which at one extremity is wide enough throughout its depth for the head of one of the screws 41 to pass therethrough. From their opposite extremities and for the greater portion of their length the slots 52 are T-shaped in cross section, so that once the disc 44 has been placed against the faceplate 38 with the screws 41 through the wide ends of the slots the disc may be turned so that the heads become located in the wider, outer portions of the T-slots. Then by tightening the screws 41 the disc 44 is firmly held for rotation with the faceplate, particularly since the T-shaped portions of the slots are so located that any slippage of the disc on the faceplate as the latter is turned brings the screws into firmer binding engagement with the T-shaped ends of the slots.

Mounted in the bore of the disc 44 and extending into the recess 39 formed in the faceplate is an adapter 53 having radial projections 54 thereon which engage corresponding radial slots formed in the disc 44. The outwardly projecting portion of the adapter 53 is of the necessary diameter to fit into the usual axial opening formed in the adjacent face of the conventional reel 42. Mounted on the standard 5a in alignment with the faceplate 38 is a bearing 55 to support one extremity of a shaft 56 the opposite end of which is mounted in the bore of the adapter 53. Secured around the shaft 56 as by a set screw 57a is a stepped rotary support 57 the steps of which are of such diameter as to fit

5 into different sized openings 42a formed in conventional reels 42. From the foregoing it will be seen that the stepped support 57 retains the reel 42 adjacent the disc 44 so that the drive pin 50 remains in engagement with the opening 51 of the reel.

10 A collapsible reel 43 is employed when the wire is to be removed therefrom in a coil prior to shipment, and is therefore generally used when relatively short lengths of wire, or relatively light wire is being handled.

15 The collapsible reel 43 includes a plate 58 substantially circularly rolled and having its opposite extremities overlapping. Formed circumferentially through the plate 58 adjacent its inner extremity 58a are a plurality of slots 59, and extending through the said plate adjacent its outer extremity are bolts 60 which project through the slots 59 and have nuts 61 on their inner extremities. These bolts hold the two extremities 58a and 58b contiguous to one another but permit limited relative movement whereby the diameter of the reel 43 formed by the said plate is varied.

20 Mounted on the inner face of the plate 58 adjacent its inner and outer overlapping extremities 58a and 58b are lugs 62 and 63 respectively. Pivoted on both lugs 62 is a locking arm 64, and pivotally connected to each side of the latter intermediately of its length and to the lugs 63 are 25 links 65. When the outer extremity of the locking arm 64 lies substantially against the plate 58 the reel formed by the latter is of normal, large diameter, as shown in Figure 9. However when the locking arm 64 is moved to its position shown in Figure 10, the inner extremity 58a of the plate is drawn farther into overlapping relation with the outer extremity 58b so that the diameter of the reel formed by the said plate is 30 reduced to permit ready removal of wire coiled therearound. Extending across the outer face of the rolled plate parallel with its axis are a number of spaced pairs of ribs 66 over which wire A extends when wound around the rolled plate. Ties B may be inserted transversely of the coil of wire and beneath the latter through the gaps formed between the adjacent pairs of ribs 66 so that the coil may be firmly tied prior to its 35 removal from the reel.

40 In Figures 8 and 9 the faceplate 38 with its forwardly projecting screws 41 are shown. Formed through a disc 67 are concentrically arranged arcuate slots 68, exactly similar in construction to the slots 52 hereinbefore described and shown, which are engaged by the screws 41 to hold the said disc upon the faceplate for rotation therewith. Projecting radially from the said disc are a plurality of radial arms 69. 67a designates a second disc having similar radial arms 69a projecting therefrom. Secured on the 45 opposed, inner faces of the arms 69 and 69a are a plurality of circularly arranged stops 70 and 70a respectively against the outer faces of which the inner margins of opposite sides of the rolled plate 58 rest to support the latter and retain it substantially coaxial with the faceplate 38. Secured to the disc 67 and projecting axially therefrom is a shaft 72 the outer extremity of which is threaded and extends through an opening 50 formed centrally through the disc 67a. Screwed onto the outer extremity of the shaft 72 is a nut 73 which holds the disc 67a against the outer edge face of the rolled plate 58, and retains the 55 opposite margin of the latter against the disc 67. From the foregoing it will be readily seen

that after removal of the nut 73 and the disc 67a the locking arm 64 is readily accessible for reducing the diameter of the rolled plate 58 and rendering wire coiled thereon readily removable.

Suitably mounted over the platform 2 is a junction box 74 into which a lead 75 extends from a source of power—not shown. Extending from the junction box 74 are leads 76, 77 and 78. The lead 76 is also connected to a suitable switch—not shown—which is so arranged that when it is closed both the leads 77 and 78 are energized. The lead 77 is connected to a reversing switch 79 from which another lead 80 extends to the motor 12; and the lead 78 terminates in a trip switch 81 from which another lead 82 extends to the motor 30.

Pivoted on one of the vertical guides 6 on the standard 5 toward its upper extremity is a lever 83 having two radially disposed arms 84 and 85 integral with it. Mounted on a spindle 86 extending from the reversing switch 79 and by rotation of which the said switch is operated, is a disc 87; and pivoted on the said disc about an axis eccentric to the disc axis is a link 88 which is also pivoted on the arm 84, so that movement of the lever 83 turns the disc 87, or vice versa. The lever 83 is so located that as the base 4 approaches its top position a trip 11a projecting from the adjacent arm 11 engages the said lever and moves it about its axis. The movement thus imparted to the lever 83 turns the disc 87 so that an operating handle 89 projecting from the latter is moved from its top position, indicated at 89a, to its mid position, thereby operating the switch 79 and stopping the motor 12.

Pivoted on the same vertical guide 6 as the lever 83 and beneath the latter is a member 90 the opposite extremity of which is pivotally connected to a rod 91 connected also to the arm 85. The member 90 is so positioned as to be turned about its axis by the trip 11a as the base 4 approaches its bottom position, thereby moving the rod 91 upwardly. When this occurs the disc 87 is so rotated that its operating handle 89 is moved from its bottom position, indicated at 89b, to its mid position, thereby stopping the motor 12.

From the foregoing it will be readily seen that automatic means are provided for limiting the vertical movement of the base 4 in both directions.

The inclusion of the trip switch 81 is for reasons of safety. The switch is arranged to prevent rotation of the faceplate 38 until the base 4 is at its bottom position. The switch 81 shown is of a conventional type including an upwardly urged member 92 which, when depressed against spring tension, closes the switch. Pivoted on the switch 81 is an arm 93 which extends over the member 92 and is retained in its raised position 93a by the said member when the base 4 is not in bottom position. However as the base approaches the bed 1 the trip 11a depresses the member 92 and closes the switch, thereby rendering the motor 30 operative.

From the foregoing it will be readily seen that when the base 4 is at its bottom position a reel 42 may be easily rolled thereonto, and that the reel is then held against accidental rotation by the ribs 4a between which it rests. The driving disc 44 is mounted on the faceplate 38 and the adapter 53 is placed in engagement with the said disc. Moreover it will be understood that different sized adapters may be used according to the size of the axial opening 42a in the ends of the reel.

The base 4 and reel 42 are raised to the required height for the shaft 56 to be inserted through the axial openings 42a formed in the ends of the reel and the opposite extremities of the shaft inserted in the adapter 53 and bearing 55 respectively. After the driving pin 50 has been inserted in the opening 51 in one side of the reel the stepped rotary support 57 is secured in position on the shaft 56 to retain the reel in engagement with the said driving pin. The base 4 is lowered and the motor 30 is then set in motion and the faceplate 38 and reel 42 rotated. When the required amount of wire has been wound onto the reel the latter may be quickly and easily demounted from the machine and lowered to the ground.

Similarly a collapsible reel 43 may also be speedily raised to position for mounting on the faceplate 38 or lowered after removal from the latter. The method of collapsing the reel 43 to permit ready removal of a coil of wire has been fully described, as also have the electrical means for operating the table and rotating the faceplate, together with the automatic features for limiting the vertical travel of the base and for preventing rotary movement of the faceplate until the base reaches its bottom position.

While in the foregoing the preferred embodiments of the invention have been described and shown, it is understood that alterations and modifications may be made thereto provided said alterations and modifications fall within the scope of the appended claims.

What I claim is:

35 1. A wire reeling machine including a bed, spaced standards fixedly mounted thereon adjacent the ends thereof, a horizontal drive shaft supported on the standards, means on the drive shaft for turning a reel therewith, guide members fixedly mounted on said bed adjacent each of said standards, vertically threaded spindles rotatably supported upon the bed by the standards, said spindles being positioned between said guide members, reversible driving means for turning the spindles, a vertically movable base mounted on said bed between said standards on which the reel is adapted to be placed for lifting into position for rotation, nuts in threaded engagement with the spindles including means thereon secured to the base whereby the latter is moved vertically upon rotation of the spindles, and means for turning the drive shaft.

55 2. A wire reeling machine including a bed, spaced standards fixedly mounted thereon adjacent the ends thereof, a horizontal drive shaft supported on the standards, means for turning the shaft, means on the drive shaft for supporting and rotating a reel, guide members fixedly mounted on said bed adjacent each of said standards, vertically threaded spindles rotatably supported by the standards upon the bed, said spindles being positioned between said guide members, a vertically movable base mounted on said bed between said standards on which the reel is adapted to be placed for lifting into horizontal alignment with the drive shaft, nuts in engagement with the threaded spindles including means thereon secured to the base whereby the latter is moved vertically upon rotation of the spindles

65 70 and the reel raised or lowered, an electric motor drive for turning both spindles, an electric circuit including the motor having a reversing switch therein, and means for opening the switch when the base reaches its upper or lower limit of travel.

75 3. A wire reeling machine including a bed hav-

ing an opening therein, a vertically movable base adapted to rest in the opening for a reel to be rolled thereonto, spaced elongated means on the base for preventing accidental rotation of the reel therefrom, spaced vertical standards on the bed, fixed guides on said standards, vertical threaded spindles mounted on the bed and supported by the standards, said spindles being movable between said guides, nuts on the spindles having means thereon secured to the base whereby rotation of said spindles moves the base vertically, a drive shaft rotatably supported on the standards, means on the drive shaft for supporting the reel for rotation therewith, means for turning the drive shaft, and means including a trip moved vertically with the base for rendering the drive shaft turning means inoperative at certain positions of said base.

4. A wire reeling machine including a bed having spaced vertical standards fixedly secured thereon, said bed having an elongated opening formed therein intermediately of its width and between said standards, a drive shaft supported for rotation by at least one of the standards, means for rotating the drive shaft, means on said drive shaft for turning a reel therewith, a base mounted for vertical movement between the standards and adapted to lie in said opening in horizontal alignment with the bed whereby the

5 reel may be rolled thereonto, means on the bed for holding the reel against accidental rolling movement thereon, a drive mechanism mounted on the bed and extending horizontally beneath the base, elevating means supported by the standards and actuated by the drive mechanism, and means on opposite extremities of the base coacting with the elevating means whereby upon movement of the drive mechanism the base is 10 adapted to be raised into position for the reel thereon to be engaged by the means on the drive shaft for turning it.

KENNETH O. MARION.
